UNITED STATES PATENT OFFICE.

MARGARET A. FRECHIN, OF GIRARD, KANSAS.

BEDSTEAD ATTACHMENT.

Application filed October 13, 1922. Serial No. 594,272.

To all whom it may concern:

Be it known that MARGARET A. FRECHIN, a citizen of the United States of America, residing at Girard, in the county of Crawford and State of Kansas, has invented new and useful Improvements in Bedstead Attachments, of which the following is a specification.

The object of the invention is to provide 10 a lifting attachment for bedsteads as a means of enabling the patient occupying the bed to assist the attendant in raising and moving the patient or to enable the patient to change his position or to rise to a sitting 15 posture without assistance and without such exertion as to be objectionable; and with these objects in view the invention consists in a construction and combination of parts of which a preferred embodiment is shown 20 in the accompanying drawings, wherein:—

Figure 1 is a view of a lifting device embodying the invention applied in the operative position to a bedstead.

Figure 2 is a cross sectional view of the 25 same.

The device consists essentially of a bar 10 extending longitudinally of the bedstead and having carried thereby a cross head 11 provided with grips or handles 12. As illustrated the cross head is slidably or movably mounted upon the bar which is of a length substantially equal to the bedstead and extends from the headboard to the footboard thereof, but obviously the cross head 35 may be secured or located in a fixed relation to the rod if preferred.

To the end that the bar may be applied to and removed from the bedstead according to whether it is needed or not to permit of

dispensing of the same when it is desired to 40 make up the bed, it is provided with terminal supports consisting of brackets having upwardly convergent arms 13 united at their meeting ends to provide sockets 14 for the adjacent ends of the bar and provided at 45 their lower remote ends with clamps 15 for engagement with the uprights or posts of the bedstead head and foot.

Obviously by grasping the grips or handles the patient may assist materially in rising to a sitting posture or in turning or moving on the bed, to thereby dispense with the services of or materially relieve the attendant or nurse in affording the patient the desired service, and yet the apparatus when not required or when the patient is not in a condition to use the same may readily be detached and stored.

Having described the invention, what is claimed as new and useful is:—

A patient lifting device for bedsteads comprising a bar for extension longitudinally of the bedstead on a transverse median line, terminal supporting brackets consisting of upwardly convergent arms provided with means for engaging the extremities of the bars at their meeting ends, said brackets at their remote ends being provided with clamps for engaging the inner sides of the corner posts of the bedstead, and a cross-head slidably mounted upon the bar and provided with grips or handles within grasping distance of the occupant of the bed.

In testimony whereof she affixes her signature.

MARGARET A. FRECHIN.
